STATIC ELECTRICAL SWITCHES

Desmond Sydney Ridler, Donald Adams Weir, and Alexander Douglas Odell, London, England, assignors to International Standard Electric Corporation, New York, N.Y.

Application March 5, 1954, Serial No. 414,406

Claims priority, application Great Britain April 30, 1953

5 Claims. (Cl. 328—96)

The present invention relates to electrical coincidence circuits.

According to the present invention there is provided an electrical coincidence circuit comprising a plurality of groups of inputs, an equal plurality of outputs each associated with one of said groups of inputs, means responsive to the coincidence of electrical conditions on all inputs of each of said groups, means responsive to the end of the electrical condition on an input of each group, and means under control of both responsive means associated with a group of inputs to energise the output associated with that group of inputs and to de-energise a previously energised output associated with any other of said groups of inputs.

According to the present invention there is also provided an electrical coincidence circuit comprising a plurality of static electrical switches, means responsive to one of said switches assuming its operated condition to cause any other operated switch to assume its non-operated condition, an output from each said switch which is energised only when that switch is operated, a group of inputs associated with each said switch, means responsive to the coincidence of electrical conditions on all inputs associated with each said switch, and means responsive to the end of the electrical condition on one of the inputs of that group of inputs on which said coincidence occurred to operate the switch associated with that group of inputs, whereby said coincidence causes one output to be energised and the previously energised output to be de-energised at the end of one of the conditions participating in a coincidence.

According to the present invention there is further provided an electrical coincidence circuit comprising a plurality of inputs, a flip-flop circuit of the bistable type which is normally in a first condition; connections from said inputs to said flip-flop such that on a coincidence of electrical conditions on all of said inputs said flip-flop is set to its second condition, and that when one of said electrical conditions ends, said flip-flop is reset to its first condition, and means responsive to said resetting to give an output.

According to our present understanding a "static electrical switch" may be defined as a device having a permanently positioned electrical path the effective impedance of which may be either of two different values, change from the one to the other value being effected by an appropriate change in a controlling electric field from one stable condition to another.

Accordingly the term "static electrical switch," as used in this specification, should be interpreted to include any device falling within the terms of this definition, and in any case includes thermistor trigger circuits, hot or cold cathode discharge tubes, hard tube trigger circuits, metal rectifier circuits and crystal triodes.

The invention will now be described with reference to the accompanying drawings, in which:

Fig. 1 is a first embodiment of the invention in which a cold-cathode tube bistable flip-flop is used.

Fig. 2 shows a three-tube multi-stable circuit also using cold-cathode tubes. In such a circuit the normal condition is with one tube discharging and all other tubes quiescent. When another tube is fired, it automatically extinguishes the other tube.

Fig. 3 shows another embodiment of the invention wherein a hard tube bistable flip-flop is used.

Fig. 4 is a further embodiment of the invention using a hard tube bistable flip-flop.

Fig. 5 shows waveforms encountered in the circuit of Fig. 4.

Fig. 6 is an enlarged view of certain of the waveforms of Fig. 5, as will be described later.

Fig. 7 is a bistable flip-flop using cold-cathode tubes each tube of which is controlled by a circuit of the type shown in Fig. 4.

Fig. 8 is a further embodiment of the invention using a cold cathode tube bistable circuit.

Fig. 9 shows waveforms encountered in the circuit of Fig. 8.

Fig. 10 is a further embodiment of the invention using metal rectifiers, such as are described in the application of K. A. Matthews, Serial No. 302,065, filed August 1, 1952, now Patent No. 2,770,763.

The circuits described have all been developed to overcome a disadvantage inherent in conventional coincidence gate circuits. In certain of these circuits, and especially where metal rectifier gates are used, it often happens that a first coincidence is required to operate a first gate, and the operated coincidence is intended to operate a further gate at a later time. If all gates give their outputs at the beginning of the coincidence, it may happen that a later gate will spuriously operate during that coincidence. This disadvantage is overcome by the present invention.

The circuit of Fig. 1 is a bistable flip-flop circuit using cold-cathode tubes CTA and CTB and having a common anode load resistor R1. If one of these tubes, e.g. tube CTA is discharging, the current flow therein produces a voltage drop across that tube's cathode resistor R2, and charges the associated cathode capacitor C1. If the other tube CTB is caused to discharge, current flowing as a result thereof increases the voltage drop across the anode resistor R1. Since C1 in the cathode circuit of CTA is charged, the anode-cathode voltage of CTA is reduced to a value less than the maintaining voltage, so CTA is extinguished. Similarly if CTA is fired when CTB is already discharging, CTB is extinguished.

Associated with these tubes are two further gate tubes G1 and G2 which are also cold-cathode tubes. The circuits of these tubes are identical, so only G1 will be described. This has in its anode circuit an inductor L1 in parallel with rectifier MR1, and in series therewith resistor R3. The first input to G1, input No. 1 is a positive pulse input which alone cannot fire G1.

The second input to G1, input No. 2 is a negative pulse input which alone cannot fire G1. When both inputs occur simultaneously, G1 is fired. The resistor R3 limits the current flowing in the circuit. The rectifier MR1 ensures that the trigger electrode of CTA cannot go negative with respect to the anode supply voltage of G1. L1 has a resistance which is low compared with that of MR1 in its forward direction so most of the current flows in L1, and hence energy is stored in the magnetic field of L1. It is assumed that when the coincidence on inputs 1 and 2 occurred, CTB was discharging.

Since G1 is a cold cathode tube the trigger electrode circuit has no influence on the tube once discharge has been initiated. Hence the ending of the pulse on input 1 has no effect on the circuit. However, when the negative pulse on input 2 ends, the anode-cathode voltage of G1 falls below the maintenance value, and G1 therefore

extinguishes. Current flow in its anode circuit therefore ends, and so the energy stored in L1 is released in the form of a positive-going half-sinusoid which, added to the normal voltage on the trigger of CTA, fires CTA and extinguishes CTB. The rectifier MR1 prevents, as described above, the trigger voltage of CTA falling below its supply value, thus holding the standing trigger bias steady whether G1 conducts or not.

The circuit of G2 is similar to that of G1. When the circuit forms part of equipment using a master pulse source, both inputs 2 and 4 could be negative-going master pulse inputs. Clearly if a coincidence occurs between inputs on inputs 1 and 2 when CTA is discharging, the half-sinusoid emitted by L1 when G1 cuts off has no effect.

Fig. 2 is a three-tube circuit having cold-cathode tubes CTC, CTD and CTE with their respective gate tubes G3, G4 and G5. The three tubes CTC, CTD and CTE are interconnected in the same manner as are CTA and CTB in Fig. 1. Such a circuit having a number of tubes of which one is discharging at once, and in which when another tube is fired the previously discharging tube is extinguished, is referred to as a multi-stable register. Thus Fig. 2 is a multi-stable register having a gate tube per tube, arranged as in Fig. 1, and so no further description of this circuit is necessary.

The circuit of Fig. 3 uses a conventional hard tube flip-flop VA—VB of the cross-coupled type. Associated with each tube is a gate triode V1, V2, and diodes D1—D2, D3—D4 respectively. Assume that VB is conducting and VA is cut off. As before, input 1 to the grid of V1 is positive-going and input 2 to the cathode of V1 is negative-going, and V1 only conducts when the coincidence occurs of a pulse on its cathode and on its grid. When V1 conducts its anode voltage falls in the usual manner, which however has no effect. However, when the pulse on either input 1 or input 2 ends, V1 cuts off and its anode voltage rises. This rise in potential is transmitted via capacitor C2 and diode D1 to the grid at VA. VA therefore conducts and cuts VB off in the usual flip-flop manner. The diodes D1 and D2 isolate VA from the negative-going pulse produced via C2 when V1 conducts, but passes the positive-going pulse produced when V1 cuts off. V2—D3—D4 function in the same manner as V1—D1—D2.

This circuit has the advantage over that of Fig. 1 in that positive or negative master pulses can be used as the termination of the pulse on either input to cause the flip over. The Figs. 1, 2 and 3 circuits thus all respond to a coincidence of a number of electrical conditions, and cause a transference of output when one of those conditions ends.

Next to be described is the circuit of Fig. 4, which will be described with reference to the waveform charts of Figs. 5 and 6. The waveforms designated by letters in Figs. 5 and 6 are those occurring at the correspondingly-lettered points on Fig. 4.

Input 1 is the master timing pulse waveform, i.e. the clock pulses, which as shown in Fig. 5, are short negative pulses. The second input, input 2, is shown as a train of longer positive pulses. If an appropriate potential occurs on input 2 coincident with the leading edge of a clock pulse on input 1, then the condition of the output will be changed on the trailing edge of the same clock pulse, whether or not the potential is then on input 2.

The two triodes VC and VD, together with resistors R4 to R9 form a bistable device of well-known type. When there is no input on input 2, that terminal will be at earth potential, and the grid of VD will therefore also be at earth potential as long as the current flowing through R5 exceeds the current through R6. If this is the case, the excess current flows through the rectifier MR3, biasing MR3 to its low resistance condition. The grid of VC is connected via resistor R7 to a positive potential E1, so the normal condition is with VC conducting. The

current flow in the common cathode resistor R4 ensures that both cathodes will be positive with respect to earth, which with the earth potential on the grid of VD ensures that VD will be held non-conducting.

The negative-going clock pulses are differentiated by C4—R7 to produce waveform A, Fig. 5. This consists of a short negative pulse at the leading edge of the input 1 pulse and a short positive pulse at the trailing edge. The clock pulse amplitude is such that the short negative pulses cannot lower the potential on the commoned cathode far enough to allow VD to pass current. If, however, the potential on input 2 is made sufficiently positive, the potential of the grid of VD will be raised to a level such that a small negative change of the common cathode potential will cause VD to conduct.

Suitable choice of the resistors R9, R6 and R5 ensures that as soon as VD conducts VC is cut off. The increased current flowing in the cathode resistor R4 renders the grid of VC more negative with respect to the cathode, and so reduces the current flowing in VC. This increases the anode voltage of VC, which via the bleeder formed by R9, R6, R5 increases the grid voltage of VD. Hence VD conducts and VC cuts off. Waveforms B and C show this.

Thus the coincidence of the positive potential on input 2 and the short negative pulse produced by differentiating a clock pulse on input 1 has switched the circuit. Neither of these conditions alone could have switched the circuit. When the positive potential on input 2 arrives half-way through a clock pulse, there is again no change in the state of VC—VD, since, as shown in Fig. 5, the negative-going differentiation product pulse has by then ended. Thus the positive potential on input 2 must occur while or before a clock pulse occurs to switch VC—VD from VC conducting to VD conducting.

To return to the circuit shown, voltages E1, E2 and E3 are so chosen that the next short positive pulse, which will be that produced at the trailing edge of the clock pulse by differentiation, which is applied to grid of VC causes VC to conduct. This again produces a cumulative action which results in VC conducting and VD cutting off.

The circuit parameters are so chosen that this state persists after the short positive pulse ends, irrespective of whether the positive potential on input 2 persists.

When VD is cut off on the trailing edge of the clock pulse, its anode voltage goes positive, as shown by the trailing edge of the negative pulse in waveform C, Fig. 5. This positive change is applied via C5 as a positive pulse to the trigger electrode of a cold cathode tube CT. This pulse, with the positive biasing potential normally applied via R10, fires CT, which therefore delivers an output from its cathode circuit by the voltage developed across cathode resistor R11.

Fig. 6 shows waveform A superimposed on waveform B, both waveforms being drawn to the same scale, and enlarged over Fig. 5. These waveforms and those of Fig. 5 are, of course, idealised waveforms, but the waveforms obtained from a practical circuit do not differ from these in more than detail.

Clearly it would be necessary to provide an arrangement for resetting CT, and this is shown in Fig. 4 by the lead connected to the anode of CT and marked "Reset," over which a negative-going pulse is applied to bring the anode voltage of CT below its maintaining voltage. One possibility which deserves mention, shown in Fig. 7, is that CT could be one "half" of a bistable gas tube flip-flop CT—CQ such as is used in the second embodiment of the invention, in which case the other "half" of the flip-flop could be controlled by a further flip-flop unit of Fig. 4 such as VC—VD. The dashed rectangles in Fig. 7 represent circuits such as Fig. 4.

To summarise the operation of Fig. 4 again, the circuit normally has VC conducting and VD cut off. This is only changed when the leading edge of a pulse on input 1

coincides with a suitable potential on input 2. This coincidence changes VC—VD to VD conducting and VC cut off. On the trailing edge of the pulse on input 1, VC—VD restores to its normal condition and this restoration operates CT to give an output. Thus the circuit in response to the coincidence of a first and a second electrical condition, stores an indication that the coincidence has occurred, and when the first condition ends it gives an output symbolic of that coincidence.

In the circuit of Fig. 8, the hard tube flip-flop VC—VD of Fig. 4 is replaced by a gas tube flip-flop CTG—CTH, which has its anodes coupled by a capacitor C6. If one tube is discharging, with its anode voltage relatively low, and the other tube is fired, the other tube's anode voltage falls. This fall in anode voltage is applied via C6 to the first tube and reduces its anode-cathode voltage below the maintaining value, thus extinguishing this tube. The waveforms applicable to this circuit appear in Fig. 9.

As before, input 1 is the master timing waveform, i.e. the clock pulses, but in this case it is a train of positive-going pulses. Input 2 is in this case a negative-going pulse, and is applied via resistor R12 to the cathode of tube CTG. The clock pulses are differentiated by C7—R13 and the result of the differentiation is applied via a further capacitor C8 to the primary of a pulse transformer T1, which acts as an inverter. Thus are produced waveforms A and B. For a reason which will be described later T1 is a step-up transformer, so that the narrow pulses applied to CTH are larger than those applied to CTG.

Waveform A is applied via R14 to the trigger electrode of CTG and waveform B is applied to the trigger electrode of CTH via resistor R15. The windings of T1 and resistors R14 and R15 are connected together and to positive E1, which supplies the positive bias for CTG and CTH trigger electrodes. The normal condition is with CTH discharging and both CTG and CT quiescent. CTG is arranged to fire when a negative pulse on input 2 coincides with the leading edge of a positive clock pulse on input 1. As will be seen, this negative pulse input is applied to the cathode of CTG across a metal rectifier MR5, which allows the cathode of CTG to be driven negative, when MR5 blocks, but holds the cathode potential of CTG substantially at earth potential when CTG is discharging.

Neither input 1 alone nor input 2 alone can fire CTG. However, when the positive-going pulse produced by differentiation from the leading edge of a clock pulse occurs while input 2 is supplying a negative pulse, CTG is fired, and this extinguishes CTH. The anode potential of CTH therefore goes positive, and capacitor C9 charges via the anode resistor R16 of CTH. On the trailing edge of the master pulse, a sharp positive pulse is applied to the trigger electrode of CTH, and re-fires this tube, whereupon CTG is extinguished via C6 and C9 discharges through the anode-cathode gap of CTH. Hence a large positive pulse is produced across the cathode resistor R17 of CTH. This is applied via C10, which with R18 differentiates the pulse, to CT, which fires to give its output. As before, resetting means is provided.

It is now clear why T1 is a step-up transformer. CTG is triggered by a combination of a positive pulse on its trigger electrode and a negative pulse on its cathode, while CTH is triggered by a positive pulse on its trigger electrode only. Hence CTH needs a larger pulse on its trigger electrode than CTG, so T1 is a step-up transformer. The negative pulses produced by the differentiation have no effect.

As before CT could be "half" of a flip-flop—in fact the blank rectangles of Fig. 7 could each include a circuit like Fig. 8.

The next embodiment of the invention, shown in Fig. 10, employs metal rectifiers of the type described in the before-mentioned application Serial No. 302,065, filed August 1, 1952.

These, like many metal rectifiers, display a negative resistance portion in the high resistance portion of their characteristics. However, unlike normal rectifiers, these devices are so constructed that this negative resistance portion occurs at a lower voltage, and the slope thereof is reduced. This permits the use of such rectifiers as two condition devices. The negative resistance portion is unstable, and consequently when the high-resistance portion of such a rectifier is examined with a cathode-ray oscilloscope, a gap in the trace appears between the two stable portions because the oscilloscope cannot follow the curve. Hence these rectifiers were referred to as negative gap diodes, and will be so designated in this specification.

15 In the circuit of Fig. 10, the pulse responsive device is a flip-flop using negative gap diodes NGA and NGB, and the output tube is replaced by negative gap diode NGT. As shown, the positive supply is such as to bias the diodes to their high resistance state. The operation 20 of this circuit is very similar to the circuit of Fig. 8. However, since the diodes are two terminal devices, the triggering must be introduced in the main and indeed only conducting path. This is permitted by decoupling rectifiers MRS5, MR6, MR7 and MR8.

25 The action of the flip-flop NGA—NGB will first be briefly described. The supply potential biases the diodes to a point near their "turnover point," i.e. the point at which a pulse of suitable potential will change their state. It will be assumed that NGA is in its high current or "on" state and NGB is in its low current or "off" state. A positive pulse applied to the upper end or anode causes NGB to pass via the unstable negative resistance region to its high current or "on" state in which it remains when the pulse ends. During this pulse, MR5 is biased 30 to its high resistance state to decouple the other "side" of the flip-flop from this pulse. When NGB comes on, the increased current in its anode resistor R20 causes a voltage drop thereacross, as a result of which a negative pulse is applied to the anode of NGA via C11 and MR7, whereupon NGA moves to its "off" state.

35 In the normal state NGB is on and NGA is off. The circuit is such that a negative potential on the cathode and a positive potential on the anode are needed to switch NGA on. This coincidence only occurs when the leading edge of a clock pulse on input 1 occurs during the negative pulse on input 2. In the present circuit negative clock pulses are used, differentiated by R21—C11 and applied directly to NGB and inverted via T2 to NGA. Hence, on the leading edge of each clock pulse a sharp 40 positive pulse is applied to the anode of NGA. If a negative potential of suitable size is also present on input 2, NGA is switched on, switching NGB off. At the end of the clock pulse the sharp positive pulse produced by differentiation restores the flip-flop to its normal state. 45 When NGB comes on, the increased current flow in R22 produces a positive output which is applied via capacitor C12 to the primary of a second pulse transformer T3. This acts as a non-phase reversing step-up transformer, feeding a diode NGT. This sets NGT to its "on" state. 50 Resetting means (not shown) restores NGT when necessary. Clearly NGT can be "half" of a flip-flop using negative gap diodes.

55 In this case T2 would be a step down transformer, ensuring that while a positive pulse on its anode can operate NGA such a pulse cannot operate NGB.

60 While the principles of the invention have been described above in connection with specific embodiments, and particular modifications thereof, it is to be clearly understood that this description is made only by way of example and not as a limitation on the scope of the invention.

65 What we claim is:

1. An electrical coincidence circuit comprising a static electrical switch having two conditions of operation, a plurality of inputs, means connected between said switch

and said inputs and responsive to the coincidence of electrical potentials on all of said inputs for preparing said switch to assume one condition of operation and responsive to the end of the said electrical potential on a particular one of said inputs for causing said switch to assume said one condition of operation, and means for producing an output when the operating condition of said switch is shifted from one of said conditions of operation to the other.

2. An electrical coincidence circuit comprising a plurality of static electrical switches, means responsive to one of said switches assuming its operated condition to cause any other operated switch to assume its non-operated condition, an output from each switch which is energized only when that switch is operated, two inputs associated with each of said switches, means associated with each two inputs responsive to the coincidence of predetermined electrical potentials on both inputs for producing a signal and for ending said signal when the predetermined electrical potential is removed from a particular one of the two inputs on which said coincidence occurred, and means connected between each said first means and the associated switch for preparing the operation of said switch in response to said signal and for causing the operation of said switch at the end of said signal, said coincidence responsive means comprising a cold cathode gaseous discharge tube, the first of the inputs associated with said coincidence responsive means being a positive potential input to the trigger electrode of said tube and the second of said inputs being a negative potential input to the cathode of said tube, said tube discharging to produce said signal as a result of a coincidence of potentials on both of said inputs and becoming quiescent to end said signal when the potential on said second input ends, and in which said means connected between said first means and the associated switch comprises an inductor in the anode circuit of said tube which delivers a pulse to the associated one of said static electrical switches when said tube is cut off, said pulse causing said switch to operate.

3. An electrical coincidence circuit comprising a plurality of groups of inputs, an equal plurality of outputs, each associated with one of said groups of inputs, first means associated with each group of inputs responsive to

the coincidence of predetermined electrical potentials on all inputs thereof for producing a signal and for ending said signal when the predetermined electrical potential is removed from a particular one of said inputs, second means associated with each group of inputs for energizing the output associated with said group of inputs and deenergizing a previously energized output associated with any other of said groups of inputs, and third means connected between said first and second means for preparing for the operation of said second means in response to said signal and for causing the operation of said second means at the end of said signal.

4. An electrical coincidence circuit comprising a plurality of static electrical switches, means responsive to one of said switches assuming its operated condition to cause any other operated switch to assume its non-operated condition, an output from each said switch which is energized only when that switch is operated, a group of inputs associated with each said switch, means associated with each group of inputs responsive to the coincidence of predetermined electrical potentials on all inputs thereof for producing a signal and for ending said signal when the predetermined electrical potential is removed from a particular one of said inputs and means connected between the first means and the associated switch for preparing for the operation of said switch in response to said signal and for causing the operation of said switch at the end of said signal.

5. A circuit as claimed in claim 4, and in which said plurality of switches is a bistable flip-flop circuit using two switches.
